SYSTEM FOR MAINTAINING CONSTANT QUANTITY RATE AND CONSTANT QUALITY OF X-RADIATION FROM AN X-RAY GENERATOR

Thomas H. Rogers, New Canaan, Conn., assignor to Machlett Laboratories, Incorporated, Springdale, Conn., a corporation of Connecticut

Application November 13, 1952, Serial No. 320,233

5 Claims. (Cl. 250—95)

This invention relates to a system for maintaining constant the quantity rate of X-radiation produced by an X-ray generator. Means is also provided by this invention for maintaining constant the quality of the radiation as well as the quantity rate thereof.

Many X-ray applications require irradiation by a constant quantity rate of X-radiation. Some applications also require relatively constant quality in the radiation. For instance, X-ray therapy is an application wherein both constant quantity and constant quality of irradiation are highly desirable. A constant quantity rate is desirable because it makes it possible to give a subject a prescribed X-radiation dosage by merely timing his exposure. Constant quality is desirable because it insures the prescribed kind of irradiation.

It has long been customary to provide regulator means to insure that the current in the filament circuit and the voltage applied across the anode and cathode of the X-ray tube in an X-ray generator are maintained constant in spite of line voltage fluctuations. It has also been possible to regulate the current through the X-ray tube so that the average current is maintained constant even with variation in effective voltage across the tube and with variation in the effects of wall charge upon the internal "bias" of the tube. However, even in those cases where the average current through the X-ray tube is maintained constant and the effective voltage across the tube is maintained constant, considerable variations in the average X-ray output of the tube have been experienced, particularly in the case of X-ray generators of the pulsating voltage type. Such variations are attributable to wall charge effects.

No satisfactory means has been devised for controlling and keeping constant the amount of wall charge in a given tube. However, I have devised a system for maintaining constant the quantity of X-radiation produced by a given generator without regard to wall charge effects. This system is independent of wall charge effects because it is dependent upon X-radiation output only. More specifically, it employs X-ray sensitive signal producing means as the criterion of circuit adjustment to correct quantitatively the X-radiation output of the generator. The X-ray sensitive signal producing means employed is advantageously an ionization chamber which is positioned in the path of the X-ray beam. The ionization chamber is in turn connected to a regulator, and the regulator is coupled to the X-ray generator circuitry.

Since X-radiation output varies with the filament current, the regulator may be coupled to the filament circuit. In coupling the regulator to the filament circuit, the regulator is adjusted to sustain a selected mean signal from the X-ray sensitive signal producing means, which mean signal is that signal produced by the desired amount of X-radiation. The regulator functions in response to fluctuations from this selected mean signal to produce whatever increase or decrease in the amount of filament current is needed to cause the X-radiation to be readjusted until it produces a signal of the selected mean value. For

2

instance, where an ionization chamber is employed, the regulator acts to increase or decrease filament current in response to variations in ionization current in such a manner as to cause the X-radiation to maintain a predetermined ionization current within the ionization chamber.

Since X-radiation varies approximately with the square of voltage applied across the X-ray tube, the regulator may be coupled to the voltage supply circuit. Accordingly, in another version of my invention, the regulator is coupled to the voltage supply circuit across the X-ray tube electrodes in such a manner that a change in the signal from the X-ray sensitive signal producing means will cause the regulator to produce whatever increase or decrease in the amount of tube potential is needed to cause the X-radiation to be readjusted until it produces a signal of the selected mean value.

Insuring the constancy of output from the X-ray tube will not necessarily insure a constant quality because the bias due to wall charges in the X-ray tube changes quality as well as quantity. Accordingly, in order to provide both constant quality and constant quantity rate of X-radiation, I provide a system which includes two X-ray sensitive signal producing means, such as two ionization chambers, located in the path of the output of the X-ray generator with a filter of a suitable material, such as copper, placed between the two chambers. Thus, the X-radiation reaching one chamber is unfiltered, whereas the radiation reaching the other chamber is filtered. If one ionization chamber is connected to a regulator which regulates the filament current in order to obtain constancy of X-radiation output as previously described, the other ionization chamber is advantageously connected to a second regulator which regulates the voltage applied to the X-ray tube. Such connections tend to produce constancy in output of both filtered and unfiltered radiation. If both the filtered and unfiltered output of the X-ray generator are constant quantitatively, the quality of output must also be essentially constant.

For a better understanding of my invention reference is made to the following drawings:

Fig. 1 illustrates schematically the essential components and circuitry of one version of my invention, this version having a regulator in the filament current supply circuit for the purpose of maintaining constant the rate at which X-radiation is produced by the X-ray generator.

Fig. 2 schematically illustrates the essential components and circuitry of another version of my invention wherein regulators are employed in connection with both the filament current supply circuit and the voltage supply circuit supplying potential across the X-ray tube for the purpose of maintaining constant both the quantity rate and the quality of X-radiation.

Fig. 3 is a circuit diagram of a simple regulator which may be employed with my invention.

Referring to Fig. 1, one of the possible circuits for maintaining constant the output rate of an X-ray generator is schematically represented showing only the portions of the generator which are pertinent to this invention. The X-ray tube 10 consists of a vacuum envelope containing an anode 11 and preferably a filamentary cathode 12. The tube 10 is advantageously placed within a shockproof, rayproof housing 13 in such a manner that X-radiation will be permitted egress from a window in the housing. A high positive potential is applied to the anode 11 of the X-ray tube when X-rays are being produced. The potential across the tube may be supplied from energy source 14 through transformer 15. The cathode 12, which is frequently a coil of tungsten wire, is supplied current from energy source 17 through transformer 18.

In the Fig. 1 version of my invention, the current supplied to filament 12 of the X-ray tube may be modified by the use of a regulator 19 which, in response to a signal from an X-ray sensitive means 20, will cause the filament current to increase or decrease. The signal producing means 20 is situated in the path of the X-ray output from X-ray tube 10 and is connected to the regulator 19. The regulator is so adjusted that a selected mean current produced in the signal producing means by the desired quantity rate of X-radiation will not produce a change in the filament current. However, upon variation from this mean current, the regulator will seek to counteract the variation and drive the X-ray output, hence the ionization current, back to the mean. More specifically, in this instance, signal producing means 20 is an ionization chamber. By virtue of the circuitry of regulator 17, an increase in the X-ray output, producing an increase over the selected mean amount of ionization current, will cause a corresponding decrease in overall current output to the primary of transformer 18, with corresponding decrease in filament current. The decrease in filament current will, in turn, produce a decrease in the amount of X-radiation thereby causing the X-radiation to drop until it reaches the level which produces the selected mean ionization current. Conversely, a decrease in the amount of X-radiation will produce a decrease in the amount of ionization current thereby causing regulator 19 to produce an increase in the filament current which ultimately causes an increase in X-radiation output until the mean value of ionization current is reestablished.

Although the signal producing member 20 of the circuit of Fig. 1 is described as an ionization chamber, it is quite possible to substitute any X-ray sensitive component capable of producing signal current fluctuations in response to fluctuations in X-ray output. For instance, a matrix of cadmium sulphide crystals might be employed in place of the ionization chamber. Various types of ionization chambers may also be employed. However, an ionization chamber employing an external and internal electrode is preferred, inasmuch as such a chamber is usually more sensitive to X-radiation. Such a chamber may be made extremely thin with windows in its walls composed of a thin film of material highly transparent to X-rays coated with a thin layer of conductive material, such as the product commercially known as "aquadag." The internal electrode may also be made extremely thin and transparent to X-rays, or it may be constructed in such a manner that the X-ray beam does not have to pass through it. In any event, the ionization chamber may be made such that the amount of attenuation produced by it will be minor compared with the attenuation produced by filter member 21. The filter 21 may be placed either between the X-ray source and the signal producing means, as shown, or beyond the filters, so that the signal producing means lies between it and the X-ray source.

Fig. 2 illustrates schematically one of the circuits of my invention necessary for maintaining both constant quantity rate and constant quality of X-ray output. Again an X-ray tube 10' having an anode 11' and a filamentary cathode 12' is enclosed within a shockproof, rayproof housing 13'. The potential across the tube is supplied by energy source 14' through transformer 15'. The excitation of the filament is supplied by energy source 17' through transformer 18'. Again filament current is modified by the action of a regulator 19' which responds to signals from ionization chamber 20' which lies in the path of X-ray output from tube 10'. An increase in X-ray output produces an increase in ionization current in chamber 20' which will cause the regulator 19' to reduce the amount of filament current supplied to cathode 12' thereby ultimately reducing the X-ray output of the tube. Conversely, decreased X-ray output will cause the regulator to increase the filament current and hence increase the output of the tube.

In this case, a second ionization chamber 23 is employed. This ionization chamber is placed on the opposite side of filter 21' from ionization chamber 20'. Ionization chamber 23 thus is subjected to the filtered X-ray output of tube 10' while ionization chamber 20' is subject to the unfiltered radiation produced by tube 10. The signal produced in ionization chamber 23 is similar to that produced in ionization chamber 20', and its effect upon regulator 24 is similar to the effect of ionization currents from ionization chamber 20' upon regulator 19'. More specifically, an increase in the ionization current over mean value in ionization chamber 23 affects regulator 24 in such a manner that it tends to reduce the voltage applied across tube 10, hence decreasing X-ray output to the level which produces the mean ionization current. Conversely, a decrease in the quantity of filtered X-radiation will produce a decrease from the mean of the ionization current thereby causing an increase in voltage across tube 10' until the quantity of X-radiation increases to the point where the mean ionization current is again produced.

Maintaining constant the quantity rate of the filtered as well as of the unfiltered radiation will result in constant quality of X-ray radiation, since the quality of radiation is defined by the ratio of the quantities of filtered and unfiltered radiation. It is possible to select quality by alteration of regulator response in either circuit to establish a different mean ionization current therein, or by varying the thickness of the filter employed, or by a combination of both methods.

As previously mentioned, for regulating quantity rate only, it is necessary to employ only one ionization chamber and one regulator coupled thereto. The regulator may be placed either in the voltage supply circuit as in the case of regulator 24 of Fig. 2 or in the filament current supply circuit as in the case of 19' of Fig. 2. The ionization chamber may be placed either above or below the filter 21'.

Various types of regulators may be employed with my invention. An electronic regulator of the saturable reactor type, such as the one illustrated in Fig. 3, is one example of a simple regulator which may be used. In order to more clearly illustrate the operation of my invention, the operation of this regulator relative to its performance in connection with my invention will be explained:

The regulator shown in Fig. 3 consists of an electrometer tube stage, an amplifier stage and a saturable core reactor. The ionization chamber is biased by battery 31 which has its positive terminal connected to the internal electrode 32 of the ionization chamber and its negative terminal connected to the external electrode 35. The signal is impressed on the grid of electrometer tube 33 by placing resistor 34 across the mutually insulated ionization chamber electrodes 32 and 35. Resistor 34 is advantageously made variable in order to allow the mean ionization current which the regulator will sustain to be varied. A by-pass condenser 36 is advantageously placed in parallel with resistance 34. Permanent bias is supplied to the cathode 37 relative to the grid 38 by battery 39. Battery 40 supplies the heater current to cathode 37 of electrometer tube 33. Anode 41 is biased positive by battery 42 which also effects a negative bias on the cathode 43 of amplifier tube 44 with respect to its grid 45. The resistance 46 impresses the signal on grid 45 of the amplifier tube 44. The battery 54 supplies heater current to the cathode 43. The plate 47 of amplifier tube 44 is positively biased by connection to battery terminal B+. The D. C. output of amplifier 44 is fed through coil 48 which surrounds saturable iron core 49. Coil 50 which also surrounds core 49 is connected in a separate circuit in series with an alternating current source 51 which corresponds to 17, 17' or 14' of Figs. 1 and 2. The terminals 52 and 53 of the regulator are thereafter connected to the primary of a transformer such as 18' or 15' shown in Fig. 2.

In operation of the regulator, the internal electrode 32

of the ionization chamber is placed at a more positive potential than the external electrode 35 due to their respective connections to the negative and positive terminals of the battery 31. Positive ions generated by X-radiation within the ionization chamber will flow to the negative external electrode 32 where they will be neutralized by taking electrons from the electrode. Conversely, negative ions or electrons will flow to the positive internal electrode 35 and be neutralized. Thus, upon irradiation of the ionization chamber current will flow through resistance 34 from the internal electrode to the external electrode. When using generators of the pulsating voltage type, condenser 36 will cause the current flow through resistance 34 to be steady rather than pulsating. The voltage drop in resistance 34 produced by the flow of current therethrough will affect the D. C. potential upon the grid 38 of electrometer tube. The grid 38 of this tube 33 will normally be held in this manner by the mean ionization current at a potential such as to produce a steady flow of electrons from cathode 37 to anode 41, which is positively biased by battery 42. This flow will in turn produce a potential upon grid 45 of amplifier tube 44 dependent upon the voltage drop across resistor 46 due to the electrometer tube anode current flowing therethrough. This potential will be sufficiently positive to permit a flow of current through amplifier tube 44 to anode 47. The anode current from amplifier tube 44 passes through coil 48 surrounding iron core 49. The magnetic flux due to the D. C. amplifier anode current of coil 48 partially saturates core 49 thereby making the A. C. inductance of coil 50 less than it would otherwise be.

It can be seen that, as the ionization current increases due to increased X-radiation, the potential drop across resistor 34 will increase, hence the potential of grid 38 will become more positive and allow more flow of current through electrometer tube 33. This increased flow through the electrometer tube will make the potential on the amplifier tube grid 45 more negative due to the increased drop across resistor 46. Hence the flow through the amplifier tube will be decreased. With the amplifier tube's anode current decreased, the magnetic saturation of the core 49 will be decreased, and hence the inductance of coil 50 increased. Thus, it may be seen that an increase in inductance in coil 50 is produced by an increase in ionization current. Hence, the current in the circuit with which the coil is in series is decreased because of the added inductance in said circuit.

The action of the regulator may be described as a feedback effect. When variation from the mean signal is severe, the feedback current from the regulator to bring it back to the mean is strong. As the variation from the mean becomes less severe, the feedback becomes less and less. There is some tendency to hunt, i. e. to overshoot the mean, but this tendency can be corrected to a large extent by the selection of circuit components having time constants which tend to damp out oscillations. Selection of the proper components having proper circuit characteristics for operation at a specified mean signal can be done by one skilled in the art. Selection by variation of resistance 34 is a preferred method.

I claim:

1. A system for maintaining constant quantity rate and

constant quality of X-radiation from an X-ray generator comprising, in combination with the X-ray generator, a pair of X-ray sensitive signal producing means arranged successively with a filter between them in the path of X-ray output of said generator, said signal producing means each being coupled through separate regulator means to the filament circuit and the voltage supply circuit, respectively, in such manner as to restore to a mean the signal in both signal producing means in order to maintain both the filtered and unfiltered radiation output constant.

2. A system for maintaining constant quantity rate and constant quality of X-radiation from an X-ray generator comprising, in combination with the X-ray generator, a first X-ray sensitive signal producing means positioned in the path of the X-ray output of said generator, a first regulator to which the first signal producing means is connected and which is in turn coupled to the filament circuit, such that the first regulator acts to increase or decrease the filament current in response to variations from a first predetermined mean signal corresponding to the signal produced by the desired quantity of X-radiation in such a manner as to reestablish said first mean signal, a second X-ray sensitive signal producing means positioned in the path of the output of the X-ray generator, a second regulator to which the second signal producing means is connected and which in turn is coupled to the high voltage supply circuit, such that the second regulator acts to increase or decrease the voltage across the X-ray tube in response to variations from a second predetermined mean signal corresponding to the signal produced by the desired quantity of X-radiation in such a manner as to reestablish said second mean signal, and an X-ray filter interposed between the first and second signal producing means.

3. A system for maintaining constant quantity rate and constant quality of X-radiation from an X-ray generator as described in claim 2 characterized in that the X-ray sensitive signal producing means are ionization chambers,

4. A system for maintaining constant quantity rate and constant quality of X-radiation from an X-ray generator as described in claim 2 characterized in that the X-ray sensitive signal producing means are placed in such position that the first signal producing means is subjected to unfiltered radiation and the second signal producing means is subjected to filtered radiation.

5. A system for maintaining constant quantity rate and constant quality of X-radiation from an X-ray generator as described in claim 2 characterized in that the X-ray sensitive signal producing means are ionization chambers which are so positioned that the first signal producing means is subjected to unfiltered X-radiation and the second signal producing means is subjected to filtered X-radiation.
